UNITED STATES PATENT OFFICE.

RICHARD SAXTON WHITE, OF NEWCASTLE-UPON-TYNE, ENGLAND, ASSIGNOR TO SIR W. G. ARMSTRONG, WHITWORTH AND COMPANY, LIMITED, OF NEWCASTLE-UPON-TYNE, ENGLAND.

TANK-STEAMER.

1,187,951.

Specification of Letters Patent. Patented June 20, 1916.

Application filed December 14, 1915. Serial No. 66,768.

To all whom it may concern:

Be it known that I, RICHARD SAXTON WHITE, a subject of the King of Great Britain, residing at the Walker Shipyard, 5 Newcastle-upon-Tyne, England, have invented new and useful Improvements in Tank-Steamers, of which the following is a specification.

This invention relates to tank steamers 10 such as are used for carrying liquids in bulk and its object is to furnish a vessel of simple and strong construction in which as much space as possible shall be available for carrying the cargo.

15 The accompanying drawing shows a vessel constructed according to my invention, only such parts as relate to the invention being depicted and described.

Figure 1 is a longitudinal section and 20 Fig. 2 a hold plan. Fig. 3 shows part of Fig. 2 to an enlarged scale and Figs. 4 and 5 are part transverse and longitudinal sections also to an enlarged scale.

25 *a* are two longitudinal liquid tight girders in the bottom of the ship, one on either side of the center line, *b* transverse girders or floors extending from one longitudinal girder to the other at suitable intervals and *c* is a central longitudinal keelson connected 30 to the floors. *d* are shelves or plates secured liquid tight to the girders *a* and *e* are the cylindrical walls of the tanks. *f* are plates riveted to the girders and floors. Each cylindrical tank is thus in communication 35 with a rectangular space extending right down to the bottom of the ship and bounded by the two longitudinal girders

and by two transverse girders. *g* are central partitions and *h* side partitions which divide the space above the plates *d* and *f* 40 not occupied by the cylindrical tanks into auxiliary tanks *i* which may be used for carrying liquid or other cargo. Where the ship narrows toward the bows short longitudinal girders *j*, nearer the middle line of 45 the ship than are the girders *a*, support the forward tank *k*.

What I claim is:—

1. In a tank steamer, the combination of 50 a pair of longitudinal girders, a plurality of transverse girders forming liquid receptacles between them, a plurality of bottomless tanks supported by the longitudinal and transverse girders and opening into said receptacles, shelves connected to the longitudinal girders and to the parts of the tanks which overlap such longitudinal girders and plates secured to the longitudinal and transverse girders and to the tanks. 55

2. In a tank steamer, the combination of 55 a pair of longitudinal girders, a plurality of transverse girders forming liquid receptacles between them, a plurality of bottomless tanks supported by the longitudinal and transverse girders and opening into said receptacles, shelves connected to the longitudinal girders and to the parts of the tanks which overlap such longitudinal girders, plates secured to the longitudinal and transverse girders and to the tanks, vertical central partitions between the tanks and vertical transverse partitions between the tanks and the sides of the ship. 65

RICHARD SAXTON WHITE.

Copies of this patent may be obtained for five cents each, by addressing the "Commissioner of Patents, Washington, D. C."
